UNITED STATES PATENT OFFICE.

MONTRAVILL D. CUMMINGS, OF COLUMBUS, OHIO.

MAIL CATCHING AND DELIVERING DEVICE.

No. 395,004.

Specification of Letters Patent.

Patented Aug. 4, 1908.

Application filed December 4, 1907. Serial No. 404,992.

To all whom it may concern:

Be it known that I, MONTRAVILL D. CUMMINGS, a citizen of the United States, residing at Columbus, in the county of Franklin and State of Ohio, have invented 5 a certain new and useful Improvement in Mail Catching and Delivering Devices, of which the following is a specification.

The object of this invention is to provide 10 improved mail catching and delivering devices and the present invention is an improvement in part upon the device shown in my Letters Patent dated January 31, 1899, and numbered 618,397.

15 The invention consists in the details of construction hereinafter described and pointed out in the appended claims, the invention not being confined to the particular embodiment of it so described, or as 20 delineated in the accompanying drawings.

In said drawings—Figure 1 shows in elevation the door-way of a railway car equipped with my invention, the position 25 of the delivering parts being that obtaining after a delivery of the mail sacks; Fig. 2 is a similar view showing the delivering parts set for discharging the sacks and the mail catching device turned into a nearly horizontal plane and therefore ready for prompt 30 operation of the delivering device; Fig. 3 is a sectional view on the line $x-x$ Fig. 2, looking toward the left, for the purpose of showing details of construction of the delivering device; Fig. 4 is a view showing the construction of the base of the catching device; Fig. 5 is a central sectional view on the line $y-y$ Fig. 4 but on a larger scale; Fig. 6 is a section on the line $z-z$ Fig. 5.

Referring more particularly to Figs. 1 to 3 inclusive, the character 7 designates the platform of the delivering device. This platform is secured to a shaft 8 that has at 40 its ends miter gears 8^a and 8^b , the shaft itself being journaled in eye-bearings 9^a and 9^b secured to the car slightly below the door-sill.

10 designates a coil spring encircling the shaft and having one end engaging the car and the other end pressing on the platform so as normally to hold the latter turned down as seen in Fig. 1. The platform is flanked by vertically-standing sides or wings 50 as seen at 11 and 12. As these wings or sides and their operating parts are symmetrical duplicates of each other, a description 55 of one will suffice for both. The side or

wing in the instance shown is constructed of an open frame covered with a woven wire lattice so that when the parts are in the position indicated in Fig. 3 it shall present as little surface as practicable to the passing air when the train is in rapid motion. But it is not, I think, absolutely necessary that the flanking wings be made as open-work, because if the parts be made sufficiently strong said sides or wings can be made of smooth solid sheet metal or wood. The side or wing has fixed to it a shaft, as indicated at 13, attached by suitable eye-bearings, as at 14^a and 14^b , to the wall of the car above the platform and adjacent the sides of the door-way, and the shaft has fixed to it at its lower end a miter gear, as at 15, that meshes with the adjacent gear on the end of the shaft 8. The wings or sides 70 are thrown inward and outward by the lowering and raising respectively of the platform, and when the platform is in its down-most position the wings or sides lie substantially parallel to the side of the car. 75 This last described position is the normal running position and offers the least resistance to the movement of the car through the air.

The platform has affixed to its underside 80 hooks 7^a and 7^b the barbs of which point toward the car, and the wings have hinged hooks 11^a and 11^b respectively the barbs of which, when the wings stand perpendicular to the side of the car, point outward, and when the sides or wings are closed toward the side edges of the platform the barbs of the hinged hooks automatically project under the shanks of the hooks of the platform and support the platform and the load of mail 85 sacks placed thereon, while the barbs of the platform hooks engage the hooks of the wings and prevent the wings from separating from the platform until the hooks of the wings are positively operated for this purpose. Each hook of a wing has a long lever arm like that seen at 11^c to the inner end of which is attached a suitable operating rod (sectional if desired) as seen at 16 extending upward to a lever 17 pivoted to a small 90 bracket 18 secured to the top of the doorway. The inner or adjacent ends of the levers at the top of the doorway are connected by a suitable chain 19 having branches to the handle of the mail catching device, which I 95 will now proceed to describe.

The catching device as I now propose it is

constructed so as to be readily reversible and therefore adapted to catch mail when the train is moving in either direction. In my proposed construction the usual bar 20 subtending or standing across the doorway is employed to receive the base or slide for supporting the usual form of mail catching hook 21. But the base or slide in the present instance is formed of two parts 22 and 22^a matching to form a passage 23 that fits on the bar 20, and beyond this a reentrant cavity 24 of circular form for the reception of a circular button at the base of the catching hook 21. The button has its edge made with two diametrically opposite holes, as at 25, into one of which is projected a spring-held pin 26. The spring-held pin has a finger-piece 26^a by which it may be manipulated to remove the pin to permit the turning of the button to the diametrically-opposite position so that the mail catching hook can be pointed in the opposite direction. The parts 22 and 22^a have, at their sides opposite those containing the mail catching hook, projections as at 27 rounded at their outer sides, and against these projections are clamped the correspondingly rounded inner sides of tangs on the handle 28. The handle is pivotally secured to the said projections by means of a spring bolt 29, the spring 29^a of which tends to hold the concave sides of the tangs yieldingly against the convex sides of the projections, so that the handle can be flexed and yield when the catcher is subjected to the violent blow incident to catching a mail sack. Shock and injury to the operator holding the handle during the mail-catching operation are thus avoided.

After mail has been discharged from the platform and the parts have assumed or are in the position indicated in Fig. 1, the platform and its wings are moved to position for the reception of fresh sacks by means of a lever 30 pivoted at 30^a near the threshold of the doorway, said lever having a long operating arm standing upward and a short arm standing outward and provided at its end with an arc extension 30^b extending through a hole 7^c in the platform, said arm having a stop 30^c to catch the platform and raise it when the long arm of the lever is pulled inward. When the platform is raised the sides or wings of the mail delivering device are, of course, thrown outward and the hooks on the sides automatically engage the hooks on the platform and the delivering device thus held in position to receive and retain the sacks ready for discharge as soon as operated by the mail catching device. After the platform has been raised the lever 30 is returned to the position shown in Fig. 3, in which position it remains by gravity and leaving the platform free to move on the arc extension 30^b when the platform is released to discharge the mail. The bar 20 is shown to be

provided with rubber cushions 20^a to take the impact of the catcher when catching a sack.

In practice, when mail is to be taken and discharged, the mail catching hook is temporarily raised by depressing the handle to or nearly to the proper position to catch the sack but not so as to operate the delivering device until the train is at the proper point to discharge the mail, when, by a further depression of the handle, the devices latching the platform are released and the mail discharged.

To prevent sacks from rolling onto the track and under the train, a low fence, as seen at 33, can be provided. Parallel tracks can be guarded in the same way.

With this construction of delivering device several sacks and several hundred-weight of mail can be instantly and safely discharged.

It will be understood that my invention is not limited in its embodiment to the specific forms of the parts shown, as these are susceptible of change without departing from the gist of the invention.

What I claim and desire to secure by Letters Patent is:

1. In a mail delivering device, the combination with the doorway of a car, a hinged platform to receive the mail to be delivered, hinged sides to flank said platform, and means whereby the same may be simultaneously opened and closed.

2. In a mail delivering device, the combination with the doorway of a car, a hinged platform to receive the mail to be delivered, cooperating hinged sides to flank said platform, means for latching said platform, and means within the car for raising said platform, said means adapted to permit the lowering of the platform.

3. In a mail delivering device, the combination with the doorway of a car, a hinged platform to receive the mail to be delivered, hinged sides to flank said platform, and gearing between the platform and flanking sides whereby the operation of the platform effects the operation of the flanking sides.

4. In a mail delivering device, the combination with the doorway of a car, a hinged platform to receive the mail to be delivered, hinged sides to flank said platform, and means for automatically latching the platform and flanking sides together when the device is brought to mail receiving position.

5. In a mail delivering device, the combination with the doorway of a car, a hinged platform to receive the mail, hinged sides to flank said platform, means for automatically latching the platform and flanking sides together when the device is brought to mail-receiving position, and manually-operative means for releasing said latching means.

6. In a mail catching and delivering device, the combination with the doorway of a

car, a hinged platform to receive the mail to be delivered, hinged sides to flank said platform, and means for automatically latching the platform and flanking sides together, a mail catching device and means between the catching device and the delivering device, whereby the delivering device can be released by operating the catching device.

7. In a mail catching device, the combination with the doorway of a car, a bar subtending the same, a slide on said bar, a sack-catching device on said slide, a handle for said slide, and means for flexibly connecting the handle with the slide comprising a concave member on one part and a convex member on the other and means for exerting a yielding pressure between said concave and convex members.

8. In a mail catching and delivering device, the combination with the doorway of a car, a hinged platform to receive the mail to be delivered, hinged sides to flank said platform, means whereby the same may be simultaneously opened and closed, and a spring to throw said platform and sides to open position.

9. In a mail catching and delivering device, the combination with the doorway of a car, a hinged platform to receive the mail to be delivered, hinged sides to flank said platform, means whereby the same may be simultaneously opened and closed, and a spring to act directly on the platform to throw it and the flanking sides to open position.

10. In a mail catching and delivering device, the combination with the doorway of a

car, a hinged platform to receive the mail to be delivered, sides to flank said platform, means for holding the delivering device in mail-receiving position, a mail catching device, and means between said catching device and delivering device, whereby the delivering device can be released by operating the catching device.

11. In a mail catching and delivering device, the combination with the doorway of a car, a hinged platform to receive the mail to be delivered, sides to flank said platform, means for automatically latching the platform and flanking sides together, a mail catching device, and means between the catching device and the delivering device for releasing the delivering device comprising arms to actuate members of the latching devices, levers on the car, and rods connecting said levers and said arms, and a flexible device between said levers and the mail catching device.

12. In a mail catching device, the combination with the doorway of a car, a bar subtending the same, a slide on said bar, a sack catching device on said slide, a handle for said slide, means for flexibly connecting the handle with the slide comprising concave members on the handle and a convex member on the slide, and means whereby a yielding pressure is exerted between said concave and convex members.
